United States Patent Office

Des. 178,775
Patented Sept. 18, 1956

178,775

ELECTRIC CORD PLUG

Andrew J. Gombar, Stratford, Conn., assignor to The Whitney Blake Company, Hamden, Conn., a corporation of Connecticut

Application June 14, 1955, Serial No. 36,500

Term of patent 14 years

(Cl. D26—1)

Fig. 1

Fig. 2

Fig. 3

Fig. 4

Fig. 5

Fig. 1 is a perspective view of an electric cord plug showing my new design;

Fig. 2 is a side elevation thereof;

Fig. 3 is a side elevation thereof taken perpendicular to the direction of Fig. 2 and looking from the right side towards the left in Fig. 2;

Fig. 4 is a bottom plan thereof; and

Fig. 5 is a section thereof taken on line 5—5 of Fig. 2.

The dominant features of my design reside in the portions shown in full lines.

I claim:

The ornamental design for an electric cord plug, substantially as shown and described.
